FIG. 2.

Zia H. Jamme
INVENTOR

BY: *A. B. M. Call.*
ATTORNEY

UNITED STATES PATENT OFFICE

92,964

DESIGN FOR A COMBINED CASKET LUG AND HANDLE

Zia H. Jammé, Chicago, Ill., assignor to Victor
Casket Hardware Company, Galesburg, Ill.

Application January 9, 1934, Serial No. 50,362

Term of patent 7 years

To whom it may concern:

Be it known that I, ZIA H. JAMMÉ, a citizen of the United States, and a resident of the city of Chicago, county of Cook, and State of Illinois, have invented a new, original, and ornamental Design for a Combined Casket Lug and Handle, of which the following is the specification, and reference being had to the accompanying drawing forming a part thereof:

Figure 1 is a front elevation of a combined casket lug and handle, showing my new design.

Figure 2 is an end elevation thereof.

I claim:

The ornamental design for a combined casket lug and handle as shown.

ZIA H. JAMMÉ.
